OUTDOOR LIGHT POST

Donald Deskey, 222 Central Park S., New York, N.Y.
10019, and Alexander Lurkis, 193-12 Nero Ave.,
Hollis, N.Y. 11423

Filed July 13, 1965, Ser. No. 86,138

Term of patent 14 years

(Cl. D48-31)

The broken line showing of a luminaire and a base in FIGURE 1 is for illustrative purposes only. FIGURES 3 and 4 are shown broken away for convenience of illustration.

We claim:

The ornamental design for an outdoor light post, as shown and described.
